UNITED STATES PATENT OFFICE.

HALBERT K. HITCHCOCK, OF PITTSBURGH, PENNSYLVANIA, ASSIGNOR TO PITTSBURGH PLATE GLASS COMPANY, A CORPORATION OF PENNSYLVANIA.

GLASS-DRAWING APPARATUS.

1,309,942.

Specification of Letters Patent. Patented July 15, 1919.

Application filed October 8, 1917. Serial No. 195,436.

To all whom it may concern:

Be it known that I, HALBERT K. HITCHCOCK, a citizen of the United States, residing at Pittsburgh, in the county of Allegheny, 5 and State of Pennsylvania, have invented certain new and useful Improvements in Glass-Drawing Apparatus, of which the following is a specification.

The invention relates to apparatus for drawing glass articles, particularly the cylinders from which window and other sheet glass is made. It has for its primary objects, the provision of improved combined drawing and take-down apparatus, where- 10 in (1) the motive power for drawing the glass articles is also utilized for swinging the take-down frame, (2) wherein the application of the motive power is automatically shifted from the drawing opera- 15 tion to the take-down operation at the end of the draw, (3) wherein the air supply pipe and the application of the operating power is taken care of in a simple and effective manner, and (4) wherein proper pro- 20 vision is made for the guiding and steady- 25 ing of the drawing mechanism. Certain embodiments of the invention are illus- trated in the accompanying drawings, wherein-

Figure 1 is a side elevation of the assembled apparatus; Fig. 2 is an enlarged front elevation of the upper part of the apparatus as shown in Fig. 1; Fig. 3 is a partial rear elevation of the lower portion of the apparatus of Fig. 1; Fig. 4 is a side elevation of the construction of Fig. 2; and Figs. 5, 6 and 7 are side elevation, front elevation, and plan views, respectively, of the upper portion of a modified construction.

Referring to the general arrangement as illustrated in Fig. 1, the principal parts of the apparatus may be enumerated as follows: 1 is a bath of molten glass from which the cylinder 2 is drawn; 3 is the bait 45 detachably secured to the weight 4 which constitutes a part of the drawing apparatus; 5 is the tilting take-down frame pivotally supported upon the hollow axle 6; 7 are the operating lines for the bait and 8 is the air supply tube therefor; 9 is the motor 50 which operates the bait and tilts the frame 5; 10 is the counterweight secured to the lower end of the take-down frame; and 11 and 11^a are stops for limiting the move- 55 ment of such take-down frame.

The counterweight 10 is carried by a pair of chains 12 (Fig. 3) secured at their upper ends to the segmental pulley members 13, so that the chains are wound around such pulley members as the take-down frame 60 moves from the position shown in Fig. 1 to horizontal position.

Mounted for rotation upon the axle 6 is the drum or reel 14 to which are secured the lower ends of the cables or lines 7. 65 Such cables or lines extend to the top of the take-down frame and around the pulley wheels 15. Connecting devices including the adjustable shackles 16 serve to connect these cables 7 with the weight 4, to which 70 the bait 3 is releasably attached. The releasable connection between the weight 4 and bait 3 may be of any desired type, but is preferably of the bayonet joint form shown in my co-pending application, Serial 75 No. 195,437, filed on October 8, 1917.

In order to provide means for stopping the upward movement of the bait the member 17 is provided at the upper end of the take-down frame through which the cables 7 extend, such member 17 being adapted to be engaged by the stops 18 carried by the connections between the cables 7 and the weight 4. To provide supports for the weight 4 and the cylinder during the take- 85 down operation the members 19, 20 and 21 are provided upon the frame, the faces thereof being curved to correspond with the curvature of the parts with which they are designed to engage. The weight 4 to which 90 the bait is attached performs the function of carrying the bait downward preparatory to a drawing operation, steadies the bait during the drawing operation, and over- hauls the lines or cables 7 and the air 95 tube 8.

Air is supplied to the tube 8 by means of the blower 22 (Fig. 3) which has its outlet end swiveled to the end of the hollow axle 6, communication being made between 100 such hollow axle and the end of the tube 8 which is wound upon the reel 14. The upper end of the tube passes around the pulley or sheave 23 and extends down and communicates with the passage 24 through 105 the weight 4 (Fig. 2). Suitable guide pulleys 25 are provided upon the frame for carrying the air supply tube.

Any desired type of motor 9 may be used for turning the drum or reel 14, although an 110

electric motor is preferred, such motor being connected by a train of reducing gearing with the pinion 26, such pinion engaging the spur gear 27 secured to the axle 6. The axle 6 is keyed to the drum 14, the tilting frame 5 being free to rotate upon the axle 6 independent of the movement of such axle.

In operation, the bait is lowered into the bath of molten glass and then drawn upward in the usual way, the motor being operated to reel up the operating lines 7 and thus raise the bait to the position shown in Fig. 1. At this time the stop members 18 (Fig. 4) engage the member 17, thus stopping the further upward movement of the bait, and the lower end of the cylinder is cut loose. The further operation of the motor causes the spur gear 27 to continue its movement in a clockwise direction (Fig. 1), but since the cable is held from movement at its upper end, the drum 14 and take-down frame 5 are rotated slowly in a clockwise direction around the axle 6, such movement causing the bait and cylinder to move over against the members 20 and 21, after which the frame is carried to a horizontal position. The bait may now be released from the weight 4 and the cylinder transferred to a support or horse upon which it is cut into sections, leaving the drawing and take-down apparatus free to be again moved back to operative position. As an alternative method of operation the cylinder may be cut into sections upon the frame 5 without removing it to a support or horse.

The invention is capable of embodiment in a number of modifications, one of which is shown in Figs. 5, 6 and 7. In this form of construction a drawing frame 28 is employed carrying the handle 29 of the bait 30. This drawing frame is operated by means of a pair of cables 31 passing over the pulleys 32 and air is supplied through a pipe 33 passing over the pulley 34, the take-down frame 35 (Fig. 5) and the mechanism for operating the lines 31 and the tube 33 being substantially the same as that heretofore illustrated and described. The drawing frame 28 is guided until it reaches its uppermost position, as illustrated in Fig. 6, by means of a guide frame comprising a pair of pipes 35 upon which the rollers 36 of the drawing frame run. These guide pipes 35 terminate adjacent the uppermost position of the frame 28 so that when the frame reaches the position indicated in Fig. 6 it is released from the guide frame and can be moved laterally and taken down along with the cylinder in the manner heretofore described. The upper ends of the pipes 35 are turned outward as indicated at 37, in order to facilitate the engagement of the drawing frame with the guides when

the frame is returned for another drawing operation.

The guides 35 serve to steady the drawing frame 28 in its upward movement, thus positively performing the function of the weight in the construction of Fig. 1, and insures the maintenance during the drawing operation of the bait in exact vertical alinement with the point in the bath from which the drawing starts. The drawing frame also provides additional weight for overhauling the cable and air supply pipe, thus performing the function of the weight in the construction of Fig. 1.

What I claim is:

1. In combination in apparatus for drawing glass articles from a bath of molten glass, a tilting take-down frame having its lower end pivoted at a point remote from said bath and inclined when in drawing position with its upper end in alinement with said bath, drawing means carried by the frame and including an operating drum mounted at the pivotal support of the frame, and a motor supported independently of the frame adjacent the pivotal support and having driving connections with the drum, a bait secured to the drawing means. 80

2. In combination in apparatus for drawing glass articles from a bath of molten glass, a tilting take-down frame having its lower end pivoted at a point remote from said bath and inclined when in drawing position with its upper end in alinement with said bath, drawing means carried by the frame, a motor supported independently of said frame having driving connections with said drawing means, a bait secured to the drawing means, and means whereby the bait is steadied during the drawing movement. 95

3. In combination in apparatus for drawing glass articles from a bath of molten glass, a take-down frame pivoted at its lower end, drawing means including an operating line carried by the frame, a bait adapted to be drawn upward by the line, and fixed vertical guideways for the bait terminating below the upper limit of movement of the bait and from which the bait is released when it passes the upper end of said guideway. 100

4. In combination in apparatus for drawing glass articles from a bath of molten glass, a take-down frame pivoted at its lower end adjacent the bath of glass, drawing means including an operating line carried by the frame, a bait adapted to be drawn upward by the line, a carriage for the bait, fixed vertical guides for the carriage, and means whereby the carriage is automatically released from the guides at the end of the draw. 110

5. In combination in apparatus for drawing glass articles from a bath of molten

glass, a tilting take-down frame, a bait, and means for lifting the bait and supplying air thereto carried by the frame and including an operating line, a flexible air supply pipe 5 and reeling means for said line and pipe mounted upon the axis of movement of the frame.

6. In combination in apparatus for drawing glass articles from a bath of molten 10 glass, a tilting take down frame, a bait, a motor fixed adjacent the frame, a reel rotated by the motor and mounted upon the axis of movement of the frame, an operating line for the bait extending around the 15 reel, and means for stopping the movement of the bait, the parts being arranged so that the application of the motive power to the reel after the upward movement of the bait is stopped causes the tilting of the frame 20 to take down the bait and cylinder carried thereby.

7. In combination in apparatus for drawing glass articles from a bath of molten glass, a tilting take-down frame, a bait, a 25 motor fixed adjacent the frame, a reel rotated by the motor and mounted upon the axis of movement of the frame, an operat-

ing line for the bait extending around the reel, and an air supply pipe also extending around the reel and having communication 30 with the bait.

8. In combination in apparatus for drawing glass articles from a bath of molten glass, a tilting take-down frame pivoted at its lower end, a rotary member mounted 35 at the pivotal support of the frame, a bait, an operating line for the bait engaging the rotary member, a motor adjacent the pivotal support of the frame, and means concentric with such pivotal support for transmitting power from the motor to the rotary member.

9. In combination in apparatus for drawing glass articles from a bath of molten glass, a tilting take-down pivoted at its 45 lower end, a bait, a reel concentric with the pivotal support of the frame, an air supply pipe carried by the reel and connected to the bait, air supply means mounted adjacent the frame but separate therefrom, and a 50 connection therefrom extending through the pivotal support of the frame and to the pipe carried by the reel.

HALBERT K. HITCHCOCK.
